F. COATES

PAPER OR PULP CONTAINER

Filed April 29, 1920

UNITED STATES PATENT OFFICE.

FREDERICK COATES, OF WYOMING, OHIO, ASSIGNOR TO THE FEDERAL PRODUCTS COMPANY, OF CINCINNATI, OHIO, A CORPORATION OF OHIO.

PAPER OR PULP CONTAINER.

Application filed April 29, 1920. Serial No. 377,702.

To all whom it may concern:

Be it known that I, FREDERICK COATES, a citizen of the United States, residing at Wyoming, in the county of Hamilton and State 5 of Ohio, have invented certain new and useful Improvements in Paper or Pulp Containers, of which the following is a specification.

My invention relates more particularly to 10 a one-piece top or bottom or head or end formed into an oblong or round cup-shape, which is adapted to be inserted onto or arranged in holding engagement with the end of a paper or pulp shell or tube to which 15 said cup-shaped head is suitably glued or otherwise adhesively sealed and given holding pressure.

The object of my invention is to provide a simple, strong, durable and economical top 20 or bottom or head or end for a paper or pulp container and one which is adapted to be easily and conveniently applied or removed. Other objects and advantages will be apparent or incidentally set forth herein.

25 My invention consists of a one-piece paper or pulp head or end or top or bottom of a paper or pulp container centrally dished with a channeled flange adapted to receive the end of the shell or tube and be pressed or 30 crimped into holding engagement thereon after first having the contacting surfaces coated with adhesive material, or in some cases, the adhesive material may be dispensed with.

35 My invention also consists in the details of construction and in the parts and combination and arrangement of parts as herein set forth and claimed.

In the drawings:

40 Fig. 1 is a vertical section through a cylindrical head forming part of my invention;

Fig. 2 is a similar view of a modification;

45 Fig. 3 is a perspective view, partly broken away, of an oblong rectangular paper or pulp box having its top and bottom provided with my novel heads;

Fig. 4 is a perspective view, partly broken away, of a cylindrical paper or pulp container embodying my invention;

50 Fig. 5 is a sectional view of a modified form of head;

Fig. 6 shows another modification; and

Fig. 7 comprises two views, a cross section and a fragmentary top elevation.

In the embodiment of my invention as illustrated, and which shows preferred constructions, the body or shell 1 or 1', as the case may be, is formed in any usual and well known manner into the shape shown. The 60 head 2 or 2' is preferably provided with a channel 3 adapted to receive the edge of the shell 1 or 1' and to be suitably secured thereto by glue or other adhesive material interposed between the adjacent walls of said 65 channel and shell, the walls of said channel being preferably compressed over the adjacent edge of the shell to form a perfectly tight and secure joint. The head may, if desired, be secured upon the shell merely by 70 compression without the use of glue or other adhesive. The head is preferably formed by being dished outwardly from the inner wall of the channel as shown in Figs. 1, 2, 3 and 4, but may be dished inwardly as shown in 75 Figs. 5 and 6. When dished outwardly, a V-shaped groove 4 is formed as shown in Fig. 1 in which the surface of the central part of head 5 is formed flush with the outer surface 6 of channel 3. If desired, however, 80 the form of the groove may be varied as shown at 4' in Fig. 2, where the outer surface of the head 5' extends in a plane below the outer surface 6' of channel 3'.

It will be apparent that my invention is 85 capable of modification without departure from its scope or spirit, as just indicated, and also as shown by reference to Fig. 5 in which the head 5'' is tapered inwardly between its flat central portion and the channeled portion. Still another modification is shown in 90 Fig. 6 in which the central portion of the head extends inwardly from the channel and straight across to form a more extended contact between the head and the shell and 95 to provide a deeper depression in the end of the container, as well as to provide a head requiring simpler tools in its construction, thereby making it more economical.

In Fig. 7, I have shown the central portion 100 of the container of concavo-convex shape with radial flutes 6 thereon to provide ornamental construction of the requisite strength.

The heads or ends are preferably formed by means of specially constructed novel tools 105 or machinery not forming a part of this invention.

These containers are preferably treated with a chemical solution for the purpose of rendering them non-leakable.

These containers are particularly adapted for use as receptacles for powders, liquids and solids. When so used, one head may be secured in position and glued or otherwise secured to the shell and having the other end open to receive the contents. When the container has been filled, the other head may be inserted and the container is then ready for use. If it is desired that the container be completely sealed after receiving the contents, the channel of the head may be coated with adhesive material and the edge of the shell inserted therein, suitable pressure being applied to the outer channel wall to cause the head and shell to become very firmly united by the adhesive.

What I claim as new and desire to secure by Letters Patent is:

1. A paper or pulp container comprising a paper or pulp tube or shell having its head or end formed from a single piece of paper or pulp dished outwardly and having a pre-formed channel upon its edge adapted to receive and engage the edge and reverse side of said shell, and means for holding said head and shell from accidental disengagement, substantially as set forth and for the purposes specified.

2. A paper or pulp container comprising a

paper or pulp tube or shell having its head or end formed from a single piece of paper or pulp and provided with a concavo-convex central portion and a pre-formed channeled rim portion, and means for securing the edge of said channeled rim portion in engagement therewith, substantially as set forth and for the purposes specified.

3. A paper or pulp container comprising a paper or pulp tube or shell having its head or end formed from a single piece of paper or pulp and provided with an outwardly curved concavo-convex fluted central portion and a pre-formed channeled rim portion and means for securing the edge of said channeled rim portion in engagement therewith, substantially as set forth and for the purposes specified.

4. A paper or pulp container comprising a paper or pulp tube or shell having its head or end formed from a single piece of paper or pulp and provided with an outwardly curved concavo-convex radially fluted central portion and a pre-formed channeled rim portion, and means for securing the edge of said channeled rim portion in engagement therewith, substantially as set forth and for the purposes specified.

FREDERICK COATES.
